FIG. I

Franklin S. Stage ^{Inventor}
Walter T. Estabrook ^{Attorney}

UNITED STATES PATENT OFFICE

1,923,172

EVAPORATOR

Franklin G. Slagel, Buffalo, N. Y., assignor to
Feeders Manufacturing Company, Inc., Buffalo,
N. Y., a Corporation of New York

Application August 13, 1930, Serial No. 475,934
Renewed January 10, 1933

3 Claims. (Cl. 62—126)

This invention relates to mechanical refrigerating systems and more particularly to evaporators.

An object of the invention is to provide an evaporator for mechanical refrigerating systems which serves to form ice forming enclosures as well as absorbing heat from air circulating thereby.

Another object of the invention is to provide an evaporator unit which includes tubes extending from the same side of a header and bent to form a plurality of partially enclosed freezing chambers lengthwise of the header.

A further object of the invention is to provide an evaporator for mechanical refrigerating systems having freezing chambers formed of a plurality of tubes formed of double parallel sections.

Other objects of the invention will appear from the following description taken in connection with the drawing, which forms a part of the specification and in which:

Fig. 1 is a side elevational view of an evaporator incorporating the invention, a portion thereof being broken away to show the refrigerant control mechanism.

Fig. 2 is a rear end view of the same.

Referring now to the drawing by characters of reference, 10 indicates a header, preferably formed of sheet copper and having an open end 30 closed by plate 11. The plate is secured in leak proof relation in any conventional manner and preferably carries the connections leading to the compressor and the condenser (not shown). An outlet opening 12 is formed through the upper portion of the plate, and an outlet tube 13 extends into the opening. Attached to the plate is a coupling 14 which is secured by cap screws 15 in open communication with the opening 12, such coupling being adapted to be connected with a conduit (not shown) extending to the compressor.

An inlet opening 16 extends through the lower portion of the plate and a coupling 17 is secured by the cap screws 18 to the plate so that it communicates with the opening. A suitable connection extends from the coupling to the condenser. Reciprocable in the inlet opening is a needle valve 19 which is connected to and controlled by an open float 20 which is pivoted at 21 to the interior of the end plate. The valve cooperates with the apertured seat member 32 to control the flow of liquid refrigerant into the header.

As the refrigerant in the evaporator absorbs heat it gaseifies and is drawn from the header through the tube 13 which is bent so that its free

end is adjacent the interior bottom of the float. As the liquid refrigerant vaporizes the float moves down allowing liquid refrigerant from the condenser to flow through the seat member because the valve is unseated, and when the liquid body 60 has been thus replenished, the float position will move the valve to close the aperture through the seat member. It will thus be seen that a substantially constant body of liquid refrigerant is maintained in the evaporator. It will also be understood that oil may travel in cycle with the liquid refrigerant and will move over the edge of the open float in the same proportion to the refrigerant as admitted, and the oil thus collecting in the float is withdrawn by suction of the compressor 70 through the tube 13.

In order to increase the heat absorbing capacity of the evaporator and to provide freezing chambers, I associate a plurality of similar bent tubes 22 with the header. The tubes are secured at one 75 end to the same side of the header in open communication with the refrigerant body, and in spaced parallel relation longitudinally of the header. The central portion of each tube is bent to provide parallel sections 23 extending transversely of the header axis, and with double parallel vertical sections 24 and with double horizontal sections 25. The vertical sections are formed alternately on opposite sides of the header and are joined by the horizontal sections, thus forming 85 superposed freezing chamber 26 partially enclosed by the tubes and extending longitudinally of the header. The upper chamber is bounded on two sides by the tubes and on a third side by the header, while the other chambers are bounded on 90 three sides by the tubes.

In order to provide a closure for pans, within the freezing chambers, I utilize sheet metal sleeves 27 which extend longitudinally of the header and in intimate contact with the adjacent tube sections. The upper sleeve is secured to the header by a plurality of brackets as indicated at 28.

It will be seen that the tubes form a plurality of superposed ice freezing enclosures, and that the evaporator can be economically manufactured as the tubes are similar and can be readily assembled with the header.

Although this invention has been described in connection with certain specific embodiments, the principles involved are susceptible of numerous other applications which will readily occur to persons skilled in the art, and the invention is therefore to be limited only as indicated by the scope of the appended claims.

What I claim is:

1. In an evaporator for refrigerating systems, a header, means for maintaining a body of liquid refrigerant in the header, a plurality of similar tubes each bent to form similar double vertical and horizontal sections, the ends of the tubes being connected to the header in communication with the liquid body and the vertical sections being alternately disposed on opposite sides of the header, and sleeves extending longitudinally in superposed relation and contacting with the tube sections on at least two sides.

2. In an evaporator for refrigerating systems, a header, means for maintaining a body of liquid refrigerant in the header and a plurality of similar tubes having the ends thereof connected to the same side of the header and in open communication with the liquid body, said tubes being bent to form similar double vertical and horizontal sections to provide a plurality of superposed freezing

20

chambers, the vertical sections being alternately disposed on opposite sides of the header which vertical sections with the horizontal sections form the walls of the freezing chamber.

3. In an evaporator for refrigerating systems, a header, means for maintaining a body of liquid refrigerant in the header and a plurality of similar tubes having the ends thereof connected to the same side of the header and in open communication with the liquid body, said tubes being bent to form similar double vertical and horizontal sections to provide a plurality of superposed freezing chambers, the vertical sections being alternately disposed on opposite sides of the header, and sleeves extending longitudinally in superposed relation in said freezing chambers and having intimate contact with the vertical and horizontal sections of said freezing chambers.
